HINGE

Fred G. Bates, Highland Park, Mich.

Application February 23, 1935, Serial No. 7,681

3 Claims. (Cl. 16—166)

This invention relates to improvements in hinges of the concealed type, and aims to provide a hinge of simple construction wherein the two hinge plates may be turned to substantially 5 180 degrees to one another.

It is an object of the invention to provide such a hinge having one relatively small and shallow hinge plate which may be mounted in a box side when only a small portion of the latter has 10 been cut away; thus I aim to provide such a hinge one plate of which may be mounted in a refrigerator box without removing any considerable portion of the insulation.

Another object of the invention is to provide 15 such a hinge wherein only a few simple parts are employed for controlling the path of movement of the two plates relative to one another; and wherein these parts are so arranged as to clear a flange which may project from the door 20 to which one hinge plate is secured in all angular positions of the hinge plates, when this flange is so arranged as to form a seal against which the other hinge plate bears when the hinge is in closed position.

25 A further object of the invention is to provide such a hinge which is simple and cheap to manufacture, and efficient in operation.

Having thus stated some of the objects and advantages of the invention I will now proceed to 30 describe it in detail with the aid of the accompanying drawings, in which:

Figure 1 is a front elevation of the hinge when open, and

Figure 2 is a plan view thereof.

35 Figure 3 is a sectional view of the parts by which the plates are connected but neglecting the latter; this section is taken on the line 3—3 of Figure 1.

Figures 4 and 5 are sections on the lines 4—4 and 5—5 respectively of Figure 2.

Figure 6 is a plan view showing the hinge in closed position, and

Figure 7 is a front elevation thereof.

Figure 8 is a section of a box with the door 45 closed and mounted upon the hinge.

Referring to the drawings, 1 and 2 designate two hinge plates. The plate 1 is of shallow box section and has apertures 3 formed therethrough for the passage of fastening means (not shown) 50 to secure the plate in a recess formed in the box C, Figure 8, to which the hinge is applied. The plate 2 consists of two spaced parallel walls 4 connected around portions of their margins by a web 5. Integral with the walls 4 are outwardly 55 projecting flanges 6 suitably apertured as shown

at 7 for fastening means (not shown) to secure the plate 2 to the door B of the box. A denotes a sealing strip upon the door B.

Through the walls 4 of the plate 2 aligned guide slots 8 inclined towards their extremities remote 5 from the flanges 6 are formed. The walls 4 are substantially parallel to two sides 9 of the plate 1. Pivoted on a pin 10 the extremities of which are mounted in the sides 9 of the plate 1 is one extremity of a segmental control member 10 11 through the opposite extremity of which a pin 12 extends which is slidable in the guide slots 8.

Pivoted upon another pin 13, the extremities of which are mounted in the walls 4 of the plate 2 15 is one extremity of a curved arm 14. The latter extends into the control member 11, and, in certain positions of the hinge, completely through the said member, which usually consists of two flat parallel portions 11a connected to one another for a part of their length by an integral rib 11b. Intermediately of its length the arm 14 is pivotally mounted upon a pin 15 the extremities of which terminate in the portions 11a of the member 11. Thus the arm 14 is pivoted 20 intermediately upon the said control member 11.

Pivoted upon yet another pin 16 the extremities of which are supported by the sides 9 of the plate 1, is one extremity of an arcuate link 17 which at its other extremity is pivotally connected by a pin 18 to the outer end of the arm 14. The link 17 in section is preferably formed similarly to the member 11, and consists usually of two parallel portions 17a held in spaced relation by an integral rib 17b. Towards its extremity 35 remote from the plate 1 the height of the link 17 is reduced to enter between two flanges 14a formed upon the extremity of the arm 14 remote from the plate 2. Since the width of both the link 17 and arm 14 for the major portions of 40 their length is preferably such that they slide freely upon the inner faces of the control member portions 11a. The arm 14 in the present instance is also formed of two spaced parallel portions 14b connected by integral webs 14c. 45

On the outer faces of the link portions 17a and the arm portions 14b adjacent their pivotal mountings on the plates 1 and 2 respectively guide strips 17d and 14d are provided so that 50 the spacing between opposed pairs of strips is such that they slide freely between the inner faces 9 of the plate 1, and of the walls 4 of the plate 2 respectively.

The operation of the hinge is briefly as follows: 55

As the hinge is moved from closed to open position the pin 12 and the extremity of the control member 11 through which it passes travel towards the flanges 6 of the plate 2; the pin 12 travelling along the guide slots 8. Due to the movement of the plate 2 the arm 14 is turned about its intermediate pivot pin 15, and the angular movement of the plate 2 relative to the plate 1 is controlled by the arm 14 and link 17. Due to the curved form of the member 11, arm 14 and link 17 clearance is provided at all times as the hinge is being opened or closed for the door flange A also indicated in Figures 2 and 6, which extends laterally adjacent one side of the plate 2 of the hinge. This flange is one commonly employed upon refrigerator doors, and is so placed that one side of the plate 1 and of the box to which the said plate is secured bears against it to form a seal when the hinge and door are in closed position. It will be further noted that the construction herein described contemplates, and permits the use of, a small and shallow plate 1 of box section; thus I provide a small plate which may be housed in a relatively small cavity in the box C without materially reducing the insulation in that portion of the wall of the box.

While in the foregoing the preferred embodiment of the invention has been described and shown, it is understood that the construction is susceptible to such alterations and modifications as fall within the scope of the appended claims.

What I claim is:

1. A hinge comprising a shallower and a deeper plate, one margin of the shallower plate resting substantially parallel and contiguous to the margin of the deeper plate when the hinge is closed, guide means carried by the deeper plate extending substantially at right angles to the aforesaid margin of the deeper plate for the greater portion of the depth of the latter, a connecting member pivoted to the shallower plate at one extremity and having its opposite extremity slidably in said guide means, an arm pivoted intermediate of its length upon said member and having one extremity pivoted on said deeper plate, and a link pivoted at one extremity upon

the shallower plate and pivoted at its other extremity to said arm.

2. A hinge comprising a shallower and a deeper plate, one margin of the shallower plate resting substantially parallel and contiguous to one margin of the deeper plate when the hinge is closed, guide means carried by the deeper plate which extend substantially at right angles to the aforesaid margin of the deeper plate throughout the greater portion of its depth, an arm having one extremity pivoted upon the deeper plate, a link one extremity of which is pivoted upon the shallower plate, the opposite extremities of said arm and link being pivoted to one another and permitting movement of the two plates through substantially 180 degrees to one another, and a connecting member pivoted to the shallower plate and slidably in the guide means whereby the sliding end of the member moves substantially from rear to front of the deeper plate to control the relative positions of said plates as the hinge is moved from closed to fully open position, said arm being also pivoted on said member.

3. A hinge comprising a shallower and a deeper plate, a curved arm pivoted at one extremity on the deeper plate, a curved link pivoted at one extremity upon the shallower plate, said arm and link being pivoted to one another at their opposite extremities to permit movement of the plates through 180 degrees, opposed guide slots formed in the deeper plate which extend throughout the greater portion of the depth thereof and are curved towards their rear extremities, a curved connecting member pivoted at one extremity to the shallower plate, said member being pivotally connected to the curved arm intermediate of the ends of both the member and the arm, said member also having its other extremity guided by said slots during the movement of the hinge whereby the relative positions of the two plates are controlled throughout the hinge movement, and the curved ends of the guide slots controlling the angularity of the adjacent faces of the two plates to one another during the commencement of the opening movement of the hinge.
